(57) **CLAIM**

The ornamental design for a magnetically actuated position sensor, as shown and described.

(**) Term: **14 Years**

DESCRIPTION

(21) Appl. No.: **29/105,828**

FIG. 1 is a right side top perspective view of the sensor, showing electrical leads in dashed outline as an environmental concomitant to the sensor;

(22) Filed: **Jun. 3, 1999**

FIG. 2 is rear elevation view of the sensor;

(51) LOC (7) Cl. **10-05**

FIG. 3 is a front elevation view of the sensor showing
